PHOTOGRAPHIC SOUND RECORDING SYSTEM AND APERTURE PLATE THEREFOR

Glenn L. Dimmick, Haddon Heights, N. J., assignor to Radio Corporation of America, a corporation of Delaware

Application April 19, 1947, Serial No. 742,545

3 Claims. (Cl. 179—100.3)

1

This invention relates to sound recording equipment, and particularly to a method of and means for recording either a negative or direct positive sound record with the same recorder.

In my U. S. Patent No. 2,311,159 of February 16, 1943, a method of and means for recording a direct positive type of sound record is disclosed and claimed. This patent describes a system wherein the light is so impressed on the film that after the normal development thereof, the track or record is in the form produced by printing from the usual negative. There are many advantages in the direct recording of such a record without going through the printing operation step. There are also advantages in the recording of a negative, and the present invention discloses a system whereby the recorder can be very rapidly adjusted so that it will record either a negative or a direct positive record according to the adjustment of the modulating element.

In my copending application Serial No. 629,294, filed November 17, 1945, a system of the general type of this invention has been disclosed and claimed. However, with the advent of double bilateral and push-pull recording and reproduction wherein the record consists of two separated longitudinal portions, the reproducing optical system utilizes beam splitting lenses which project the light from each longitudinal section of the record to each of two portions of a photoelectric cell or one of two separate cells. In such a beam splitting optical system there is a small narrow longitudinal portion of the track which cannot be utilized because of the physical division or septum between the splitting optical cylinders. Thus, if a single section sound record is reproduced in a push-pull optical system, and particularly the type of record made with the system disclosed in my above mentioned copending application, low modulations are either distorted or entirely eliminated during the reproduction. Furthermore, the system is particularly critical to film weave.

The present invention, therefore, provides a negative-positive recording system which has all the advantages of my prior system while the record so made may be reproduced in either a single photocell or a push-pull photocell reproducing system. That is, the two sections of the push-pull photoelectric cell are connected in parallel for the double bilateral type of record such as made with the present invention, and then switched to a push-pull connection for regular push-pull tracks.

The principal object of the present invention,

2

therefore, is to facilitate the recording of film sound records.

Another object of the invention is to provide an improved recording method and system for producing either a direct positive or negative sound record with the same apparatus.

A further object of the invention is to provide an improved sound recording aperture for recording either a negative or positive sound record which is reproducible in any type of reproducing sound system.

A still further object of the invention is to provide a sound recording system which may be rapidly changed from a negative to a direct positive system, or vice versa, the record of which is reproducible in either a single photocell or push-pull reproducer.

Although the novel features which are believed to be characteristic of this invention will be pointed out with particularity in the appended claims, the manner of its organization and the mode of its operation will be better understood by referring to the following description read in conjunction with the accompanying drawing, forming a part hereof, in which:

Fig. 1 is a diagrammatic view of a recording system embodying the invention;

Fig. 2 is a plan view of the slit mask showing a light beam superimposed thereon;

Fig. 3 is a section of the negative sound track made in accordance with the invention; and

Fig. 4 is a section of a direct positive sound track made in accordance with the invention.

Referring now to the drawings in which the same numerals refer to like elements, the output of a microphone 5 is fed into an amplifier 6, and then directly over conductors 7 to a galvanometer 8. The output of amplifier 6 is also fed to a noise reduction amplifier 10, and then over conductors 11 to the galvanometer 8, it being well understood that the galvanometer mirror 12 is vibrated both in accordance with the instantaneous values of the sound waves and the envelope of the sound waves. The remaining portion of the recording system includes a light source 14, a collecting lens 15, a mask plate 16, and a lens 18, together with a lens 20, a slit mask plate 21, a lens 23, and a film 22. In such a system, light from the lamp 14 is formed into a W shaped light beam by the aperture 24 in the mask 16, then projected on the mirror 12 of the galvanometer 8 from which it is reflected to the slit mask 21, the light emerging through a slit 26 and slits 27 and 28 being impressed on the film 22, as will now be described.

Referring now to Fig. 2, the slits 26, 27 and 29

are shown in the mask 21 together with the superimposed W shaped light beam shown by the lined portion 30. The aperture has irregular side edges and parallel end edges. In the position of the light beam in this figure, fifty percent of the slit 26 is illuminated. However, because of the noise reduction bias, the no signal or zero position of the light beam is such that only the tip portions *a* and *b* of the beam pass the slit 26 to produce the so called bias lines. As the amplitude of the signal increases, the output of the noise reduction amplifier 10 moves the average position of the beam downwardly in accordance with the envelope of the signal as the beam vibrates in accordance with the instantaneous values of the signal. The result of this type of recording produces a double bilateral record such as shown in Fig. 3, wherein the light impressed on parallel portions 40 and 41 of the sound record are opaque when developed and the remaining portion of the sound track area of the film is transparent. When this film is printed, however, the reverse densities occur on the print as is well known in the art. To illustrate the length of the slit 26 as projected on the film, a section 42 of the modulations are shown overshot, the slit length being represented by the distance between the flat ends.

Referring again to Fig. 1, the position of the galvanometer 8 is controlled by a manual screw 32, the galvanometer being adapted to pivot in any suitable manner, such as on or about point 33. With the galvanometer adjusted by the screw 32 so that the light beam 30 is impressed on the slit plate 21 with respect to the slit 26, as shown by the lined portion in Fig. 2, a negative type of record, as shown in Fig. 3, will be produced. It will be noted that the perpendicular distance between the ends of slit 26 and the lower points of the light beam 30 is the same as the distance between the slit 26 and the slits 27 and 28. Thus, no light will pass through the slits 27 and 28, even during overloads up to one hundred percent, such overloads usually being prevented by the limitations of the galvanometer and the amplifiers.

Now, if it is desired to record a direct positive type of record, such as shown in Fig. 4, and which will be the same as the print made from the negative shown in Fig. 3, it is only necessary to tilt the galvanometer 8 slightly by the screw 32, so that the light beam 30 assumes the position shown by the dotted lines 35 in Fig. 2. It will be observed that when the beam is in position 35, the slit 26 again passes light along fifty percent of its length, but the light now passes the slit at its ends and central portion rather than in its former portions. It will also be noted that light is now projected through slits 27 and 28. However, because of noise reduction bias, at times of no signal, or zero position of the light beam, light is passed by the entire slit, except for two short, narrow portions corresponding to the points shown by the bias lines *a* and *b*, light being passed by slits 27 and 28 at all times. This adjustment of the galvanometer can be made very rapidly, while the noise reduction adjustment, or bias, is always for the same amount and in the same direction, regardless of the type of record to be recorded.

The result of the shifting of the galvanometer so that the light beam 30 takes the position

shown by the dotted lines 35 is a record such as shown in Fig. 4, wherein the two modulated portions 43 and 44 will be transparent and the remaining portion, up to the outer ends of slits 27 and 28, will be opaque upon the development thereof. To again illustrate the length of slit 26, overshooting of the section 45 is shown similar to section 42 in Fig. 3.

In Fig. 1, two vertically elongated apertures 38 and 39 are shown through which light from the source 14 is projected and after modulation by the mirror 12 is projected on a mirror 37 positioned near the end of the slit plate 21. This light may be used for monitoring in the manner disclosed in my copending application Serial No. 629,295, filed November 17, 1945, or the slit mask 21 may have a window therein through which the monitoring beam is projected and reflected to an observation medium in accordance with a system shown in L. T. Sachtleben copending application Serial No. 742,360, filed April 18, 1947. The upper monitoring aperture 38 is used when monitoring the recording of a negative record, and the lower aperture 39 is used when monitoring the recording of a positive record, as disclosed in my above mentioned copending application.

I claim:

1. A sound recording system adapted to record different types of sound tracks comprising a source of light, means for forming light from said source into a beam, a vibrator for said light beam, a film on which portions of said light beam are impressed, and a mask having a light slit therein for determining the portions of said beam impressed on said film, said first mentioned means including a mask having a W-shaped aperture therein, light passing one irregular edge of said W-shaped aperture recording a negative type of record and light passing the other irregular edge of said W-shaped aperture recording a direct positive type of record, the spacing of said edges of said beam being greater than the movement of said beam at said slit mask during the recording of one of said records.

2. A sound recording system in accordance with claim 1 in which double bilateral sound records are produced by said recordings.

3. A sound recording light-shaping aperture plate for recording either a double bilateral negative record or a double bilateral positive record comprising an opaque plate having an opening therein in the shape of the letter W, the ends of the aperture having edges parallel to one another and perpendicular to the longitudinal axis of the aperture, the width of the aperture between the irregular edges of the W being substantially one-half of the length of the aperture along the longitudinal axis thereof.
